CLAIM

The ornamental design for a front panel, as shown and described.

DESCRIPTION

FIG. 1 is a top plan view of a front panel showing our new design;

FIG. 2 is a front elevational view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a front, top, right isometric view thereof; and,

FIG. 8 is a rear, top left isometric view thereof.

The broken line showing of the rear light pipe mount assembly and rear structural ribs is for illustrative purposes only and forms no part of the claimed design.
